FREDERICK M. CONRAN, OF ELIZABETH, NEW JERSEY, ASSIGNOR TO THE METALS PLATING COMPANY, OF NEW YORK, N. Y., A CORPORATION OF NEW JERSEY.

AUTOMATIC SHEET-FEEDING MECHANISM.

1,301,656.

Specification of Letters Patent. Patented Apr. 22, 1919.

Original application filed October 31, 1917, Serial No. 199,416. Divided and this application filed March 19, 1918. Serial No. 228,381.

To all whom it may concern:

Be it known that I, FREDERICK M. CONRAN, a citizen of the United States, residing at 778 Newark avenue, Elizabeth, in the county of Union, State of New Jersey, have invented certain new and useful Improvements in Automatic Sheet-Feeding Mechanism; and I do hereby declare the following to be a full, clear, and exact description of the invention, such as will enable others skilled in the art to which it appertains to make and use the same.

The present invention relates to sheet feeding mechanism and has for an object the provision of a mechanism whereby sheets of material may be put in position to be lifted one at a time from the top of a stack of sheets and fed successively therefrom.

In order to bring the top sheet of the stack in proper position to be removed, the invention comprises feeding devices by means of which the stack of sheets is raised after each top sheet has been removed. The mechanism may be used for a wide variety of purposes and in combination with many forms of mechanism in which the sheets are to be subsequently operated upon.

Other objects and advantages of the invention will appear more clearly from a detailed description of certain preferred embodiments thereof as illustrated in the accompanying drawings, in which Figure 1 is a side elevation of one embodiment of the machine as viewed from the right showing the same in combination with the mechanism to which the sheets of material are to be fed for subsequent treatment; Fig. 2 is a side elevation of the same machine as viewed from the left; Fig. 3 is a front elevation of the machine; and Fig. 4 is a sectional elevation along the line 4-4 of Fig. 3.

Referring to the drawings, in which similar reference characters denote similar parts throughout the several views, 20 indicates the foundation or base plate of the machine above which project side frames 21. Each side frame is provided with a vertical slot. The edges of the slots are provided with guideways 22 which extend slightly beyond the faces of the side frames. Upon the inside face of each side frame and adjacent one edge of the slot is a guideway 23, the face of which is at right angles to the face of guideway 22. Mounted to slide upon

each side frame 21 is a bracket 24 provided with rollers 25 fitting between and engaging the guideways 22 and other rollers 26 which engage the guideways 23. A cross bar 27 connects the brackets together and holds them in position with their rollers 26 against the guideways 23. Each bracket is provided with inwardly extending shelves 28 which in connection with the cross bar 27 support a table 29 which may be adjusted transversely of the machine by means of bolts 30. The sheets of material indicated by A are placed upon this table.

On the rear face of each bracket 24 is a rack bar 31 meshing with pinions 32 mounted on stub shafts 33 and 34 mounted in bearings on the ends of brackets 35 and 36 respectively, attached to and projecting from the sides frames 21. Mounted on shaft 33 between bracket 35 and the corresponding side frame 21 is a gear 37. A similar gear 38 is mounted on shaft 34 between the bracket 36 and corresponding side frame of the machine. The gear wheels 37 and 38 are driven by pinions 39 mounted on shaft 40 which extends across the machine and is mounted in suitable bearings in the side frames and on the left hand side of the machine is extended through a bearing on the upper end of bracket 36. Splined on the shaft 40 is a clutch member 41 having associated therewith an operating lever 42. This clutch member is adapted to engage a co-operating clutch member 43 fastened to gear 44 which is loosely mounted on the shaft 40. The gear 44 engages a pinion 45 fixed to a shaft 46 mounted in bearings in the bracket 36 and the corresponding side frame 21. Also mounted on the same shaft is a ratchet wheel 47. Loosely mounted upon the shaft 46 between a pinion 45 and ratchet wheel 47 is an arm 48 which carries pawl 49 which engages the teeth of ratchet wheel 47. A holding pawl 50 is mounted on the side frame 21 to prevent reverse rotation of the ratchet wheel.

The automatic feeding mechanism is, by way of illustration, shown in combination with a machine for coating the sheets of material. Only the forward end of the coating machine is shown in the drawings. This portion comprises a frame 51 in which is mounted a shaft 52 adapted to be driven by a sprocket wheel 53 and chain 54 running

to the other sprocket wheel, not shown, associated with the driving mechanism of the coating machine. Mounted upon one end of the shaft 52 is a cam 55 adapted to engage 5 a roller 56 on the end of an arm 57 pivoted at 58 to the frame 51 on the coating machine. Pivoted to arm 57 and to arm 48 at 60 is a link 61. To limit the forward travel of arm 57 an adjusting screw 62 is 10 mounted in a bracket 63 attached to the frame of the coating machine. Arm 57 is drawn against the end of adjusting screw 62 by a spring 64.

For the purpose of permitting the table 29 to be lowered in case it is desired to obtain access to the sheets of material, a hand wheel 65 is mounted on shaft 34 inside of frame 36. When the clutch members 41 and 43 are disengaged, gear wheels 37 and 38 and the pinions and rackbars which connect these gears to the sliding frame which supports the table, would be free to turn under the weight of the table and the sheets thereon. To prevent this action from taking place, a brake shoe 66 engaging the hand wheel 65 is provided. This brake shoe is pivoted to the side frame 36 at 67 and its free upper end is by means of a link 68 connected to a lever 69 pivoted at 70 to the extension of the side frame. An arm 71 is attached to the side frame 36 by bolts 72 and this arm is provided near its upper end with spring arm 73 which extends adjacent the lever 42 by which the clutch member 41 is operated. This spring arm is provided with a lug 74 which engages a lug 75 near the upper end of arm 69 when the clutch lever 42 is in the position to throw the clutch members into engagement with each other. When the clutch lever is thrown so that the clutch members are disengaged, spring arm 73 will be pushed outwardly to disengage the lugs 74 and 75 and lever 69 will be drawn toward the arm 71 by a spring 76 connecting the upper end of the lever and the upper end of this arm. Movement of lever 69 will be communicated through link 68 to the brake shoe 66, thus causing the latter to bear firmly against the hand wheel 65 and prevent any rotation of the gears associated with this hand wheel, and hence will prevent any downward movement of the table upon which the sheets are supported. Whenever the clutch lever is thrown to connect the clutch members together, the brake is released by restoring the lever 69 to its position in engagement with the lug 74 on the spring arm 73.

The apparatus thus far described is intended for elevating the table 22, upon which the sheets of material are carried, by a step by step mechanism to cause the top of the pile to be brought into position to be removed from the pile. The shaft 52 is continuously driven from the coating machine

and the cam 55 engages the roller 56 on the end of arm 57 once during each revolution of shaft 52. The movement imparted to arm 57 will, through the link 61, cause a corresponding movement of the arm 48, and the pawl 49, mounted thereon, will engage the ratchet wheel 47 to rotate the same step by step. This movement of the ratchet wheel will be communicated through shaft 46 and pinion 45 to gear wheel 44, but unless the clutch members 41 and 43 are in engagement the rotation of gear wheel 44 will have no effect in moving the table on which the sheets are supported. If, however, the clutch members 41 and 43 are drawn into engagement by means of hand lever 42, the step by step movement of gear wheel 44 will be communicated to the shaft 40, and the lever will, through the pinions 39, cause the corresponding step by step movement of the gear wheels 37 and 38 which will be imparted to the pinions 32 mounted upon the same stub shafts 33 and 34 as are these gear wheels. The result will be that the rack bars 31 which engage the pinions 32 will be given a step by step movement upward to gradually lift the table 29 upon which the sheets of material are placed. The magnitude of each successive lifting movement of the table may be controlled by the adjusting screw 62 which determines the movement imparted to the ratchet wheel 47 upon each oscillation of the arm 57. The movement imparted to the ratchet 47 is, through the proper proportioning of the gears and pinions of the apparatus, translated into the correct vertical movement of the sheet holding table to cause the latter to advance a distance just sufficient to bring successive sheets into position to be removed. This distance will correspond to the thickness of the sheets which are to be removed from the stack plus such additional movement as may be required to make up for the fact that the sheets may be slightly separated due to impurities or rust upon their surface. By proper calibration of the adjusting screw 62, the lifting action of the apparatus may be accurately adjusted to suit the particular sheets that are being removed.

The mechanism for removing the sheets one at a time from the top of the stack of sheets comprises a suction device for lifting the rear edge of the topmost sheet into position to be engaged by traveling gripping members which convey the sheet off of the top of the stack of sheets, the forward movement of the sheet being facilitated by an air blast which is directed under the topmost sheet after its edge has been lifted by the suction device, but as the details of this particular mechanism, as well as the stop mechanism which automatically engages the front edge of sheets lying beneath the topmost sheet, are not important in this connection, they will not be described in detail.

sheet, are included in the subject matter of my copending application Serial No. 199,416, the same will not be further described herein.

5 I claim—

1. In sheet feeding mechanism, the combination of a pair of slotted supports provided with guides along the edges of the slots and upon the inner face of each support adjacent one edge of the slot therein, movable members mounted upon the supports and having rollers within the slots engaging the guides along the edges thereof and other rollers engaging the guides upon the inner faces of the supports, sheet holding means adjustably mounted between and supported upon the movable members, a rack bar attached to each movable member, a set of gears operatively connected to each rack bar, and means for producing an intermittent actuation of the said sets of gears to impart a step-by-step movement to the rack bars to raise progressively the sheet holding means.

2. In sheet feeding mechanism, the combination of a pair of supports, means slidably mounted on said supports for holding a stack of sheets, a rack bar attached to each side of the holding means, a pinion engaging each rack bar, a gear wheel associated with each pinion, a shaft provided with pinions engaging both of said gear wheels, a ratchet wheel, a gear loosely mounted on said shaft, a pinion connecting said ratchet wheel to the last named gear, a clutch for connecting the last named gear to the shaft upon which it is loosely mounted, a pawl associated with the ratchet wheel, a driving shaft, means operated by said driving shaft and connected to the pawl whereby an intermittent movement may be imparted to the ratchet wheel to cause an intermittent movement of the sheet holding means, and means for adjusting the movement of said pawl to control the lifting movement imparted to the sheet holding means.

3. In sheet feeding mechanism, the combination of a pair of supports, members slidably mounted on the supports, sheet holding means mounted between and supported upon the members, brackets attached to the outside of each support, a stub shaft mounted in each bracket, a rack bar associated with each member, a pinion mounted on each stub shaft engaging the corresponding rack bar, a gear wheel on each stub shaft, a shaft mounted in said supports, pinions on said shaft engaging both of said gear wheels, a ratchet wheel, clutch mechanism for operatively connecting said ratchet wheel to said shaft, a driving shaft, and means operated by the driving shaft for actuating the ratchet wheel to impart an intermittent movement to the shaft mounted in the supports to cause an intermittent movement of the sheet holding means.

4. In sheet feeding mechanism, the combination of a pair of slotted supports, guideways at the edges of the slots, a movable member slidably mounted on each support and provided with rollers engaging the guideways, means mounted between the movable members for holding a stack of sheets, a rack bar attached to each movable member, a pinion engaging each rack bar, a gear wheel for driving each pinion, a shaft provided with pinions engaging both of said gear wheels, and means for producing an intermittent actuation of said shaft to impart a step-by-step lifting movement to the rack bars and movable members.

5. In sheet feeding mechanism, the combination of a pair of slotted supports provided with guides along the edges of the slots and upon the inner face of each support adjacent one edge of the slot, movable members mounted upon the supports and having rollers within the slots engaging the guides along the edges thereof, other rollers engaging the guides upon the inner faces of the supports, sheet holding means adjustably mounted between and supported upon the movable members, a rack bar associated with each movable member, a pinion engaging each rack bar, a gear wheel for driving each pinion, a shaft provided with pinions for driving both of said gear wheels, a clutch member slidably mounted on said shaft, a co-operating clutch member rotatably mounted on said shaft, means for putting said clutch members into engagement with each other, a gear associated with the rotatable clutch member, a pinion meshing with said last named gear, a ratchet wheel operatively connected to said pinion, a pawl associated with the ratchet wheel, a driving shaft, a cam on the driving shaft, means operated by the cam and connected to the pawl whereby an intermittent movement may be imparted to the ratchet wheel to cause an intermittent lifting of the sheet holding means when said clutch members are in engagement, and means for adjusting the movement of said pawl to control the lifting movement imparted to the sheet holding means.

6. In sheet feeding mechanism, the combination of a pair of supports, means slidably mounted on said supports for holding a stack of sheets, a rack bar attached to each side of the holding means, a pinion engaging each rack bar, a gear wheel for driving each pinion, a shaft provided with pinions for driving both of said gear wheels, a ratchet wheel, clutch mechanism for operatively connecting said ratchet wheel to said shaft, a pawl associated with the ratchet wheel, a driving shaft, a cam on the driving shaft, means operated by the cam and connected with the pawl whereby an intermittent movement may be imparted to the ratchet wheel to cause an intermittent lifting of the sheet

- holding means, and means for adjusting the movement of said pawl to control the lifting movement imparted to the sheet holding means.
- 5 7. In sheet feeding mechanism, the combination of supports, means movably mounted on the supports for holding a stack of sheets, rack bars associated with said sheet holding means, a set of gears operatively connected to 10 each rack bar, a shaft and gears for driving said sets of gears in unison, a shaft adapted to be continuously driven and provided with a cam, a ratchet, a set of gears operatively connected to said ratchet, a pawl associated 15 with said ratchet and adapted to be intermittently actuated by said cam, and means for operatively connecting the first named shaft and gears to the last named set of gears to cause an intermittent movement to be imparted to the sheet holding means.
- 20 8. In sheet feeding mechanism, the combination of supports, means movably mounted on the supports for holding a stack of sheets, rack bars associated with said sheet holding means, a set of gears associated with the rack bars, a shaft adapted to be continuously driven, a second set of gears, means actuated by the shaft for producing an intermittent movement of the second set of gears, means 25 for operatively connecting the first named set of gears to the second set of gears to cause an intermittent movement to be imparted to the sheet holding means, and braking means for preventing motion of said first set of gears when disconnected from the second set of gears.
- 30 9. In sheet feeding mechanism, the combination of supports, means movably mounted on the supports for holding a stack of sheets, 35 rack bars associated with said sheet holding means, a set of gears associated with the rack
- bars, a shaft adapted to be continuously driven, a second set of gears, means actuated by the shaft for producing an intermittent movement of the second set of gears, means 45 for operatively connecting the first named set of gears to the second set of gears to cause an intermittent movement to be imparted to the sheet holding means, braking means for preventing motion of said first set of gears when 50 disconnected from the second set of gears, and means under control of the connecting means for controlling the operation of the braking means.
10. In sheet feeding mechanism, the combination of a pair of supports, members slidably mounted in said supports, sheet holding means mounted between and supported upon said members, a stub shaft associated with each support, a rack bar on each member, a pinion on each stub shaft engaging the corresponding rack bar, a gear wheel on each shaft, a shaft mounted in said supports and provided with pinions engaging said gear wheels, clutch members associated with said 60 shaft, a ratchet wheel operatively connected to one of said clutch members, means for producing an intermittent actuation of the ratchet wheel to impart a step-by-step lifting movement to the sheet holding means, a hand wheel associated with one of said stub shafts, a brake operatively connected to said hand wheel, and operative connections between said clutch members and said brake so constructed that when said clutch members are 65 disengaged from each other said brake will be in engagement with said hand wheel to prevent downward movement of said sheet holding means.
- 70 In testimony whereof I affix my signature. 75
- FREDERICK M. CONRAN.
